UNITED STATES PATENT OFFICE.

AUGUST G. FROMUTH, OF PHILADELPHIA, PENNSYLVANIA, ASSIGNOR TO ALVA CARPET & RUG COMPANY, A CORPORATION OF PENNSYLVANIA.

YARN AND FABRIC AND PROCESS OF PRODUCING.

1,336,516.

Specification of Letters Patent. Patented Apr. 13, 1920.

No Drawing.

Application filed May 19, 1916. Serial No. 98,576.

To all whom it may concern:

Be it known that I, AUGUST G. FROMUTH, a citizen of the United States, residing at Philadelphia, in the county of Philadelphia and State of Pennsylvania, have invented 5 certain new and useful Improvements in Yarns and Fabrics and Processes of Producing, of which the following is a specification.

10 My invention relates to a novel composite yarn and to fabrics woven therefrom, as well as to the improved process whereby the same are produced or manufactured.

15 My invention presents the advantages of convenience and cheapness in manufacture, as compared with the nearest approaches thereto which have been known heretofore; and, moreover, the use of my invention makes it possible to produce effects of a 20 highly decorative and entirely novel character.

25 My improved composite yarn is produced by first twisting together a plurality, for example, two, three or more single strands 30 of different natural colors, but of the same nature of material, as, for instance, undyed or natural white wool, undyed or natural gray wool and undyed or natural dark gray wool, or other combinations of natural 35 colors, in the same kind of material, after which I apply color to the combination thus produced. The color may be applied by any well known process of drum printing, roller printing, or any other printing or 40 dyeing process and may be printed or dyed either continuously or at intervals by means and in a manner well known in the manufacture of tapestry or velvet carpets or rugs, whether printed by the well known drum printing process, roller printing process or any other printing or dyeing process.

45 The color, being applied to an undyed thread or yarn of two or more different natural tints but all of the fibers of which are of the same nature, such as wool, produces a 50 yarn of a corresponding color effect of variegated appearance. If solid blue be used, for instance, the composite will present three different shades of blue, twisted together.

Heretofore composite yarns have been used, the single members or threads or strands of which were separately colored or dyed before being twisted together, and 55 I make no claim to such a yarn. Composite

yarns made in this manner, however, are not susceptible of use in carpet and rug weaving with the same advantageous results as is my improved yarn; and, moreover, the older process is slower and more 60 costly than mine.

Also heretofore yarns of different natural colors have been woven into a fabric to produce or to help in producing a pattern, but this practice is entirely unrelated to 65 and forms no part or feature of my invention and I do not claim it, and obviously the advantages resulting from my invention cannot be obtained in this way.

Also heretofore it has sometimes been the 70 practice to combine in one thread materials of different natures, such as jute and linen, or jute and cotton, or all three of these different materials, so that when dye is applied a varied effect is produced by reason 75 of the fact that the fibers being of different natures some of them take the dye more readily than do others, but this is wholly outside of my invention and I make no claim thereto. My invention is based upon 80 the varied natural colors of different fibers of the same nature, such as wool, and which therefore have like properties as to their readiness in taking a dye.

85 For instance, in carrying out my invention, the undyed composite woolen yarns, for use in the figuring warp of a carpet or rug, may have patterns printed thereon by the well known drum print or pulley process, roller printing process or by any other 90 process, whether by printing or dyeing, whereby a figure of variegated color may be produced on a ground of another variegated color. This effect is superior to anything hitherto produced in tapestry, velvet, Ax- 95 minster, body Brussels or Wilton carpets or rugs and cannot be obtained as economically or have as artistic an effect by use of yarns formed from strands dyed separately and then twisted together in the manner 100 heretofore employed; and it is entirely out of the question to employ materials having different natures, wool being the only thing suitable, as is well known in the art.

Furthermore, I can combine the effects 105 last described with those produced by my prior invention set forth in my application for patent, Serial No. 51,506, filed September 18, 1915, wherein narrow sharply defined stripes of color may be produced wherever 110

desired in the length of the yarn, and may be located in juxtaposition to narrow sharply defined unprinted stripes. This combination achieves a further enhancement 5 of the effects possible.

A further advantage of producing a variegated yarn by my improved process is found in the different and improved esthetic character of the yarn, which has a sun-
10 light and shadow effect, having a more lustrous appearance and an improved texture. In the older process, the raw material goes first to the spinner who makes the single threads or strands, then to the dyer who
15 dyes these in the single form and then to the manufacturer who twists the differently colored threads together. No further color can be successfully applied to these composite yarns, as any additional color app-
20 plied to these dyed, composite yarns deadens the color effect, makes it lose its luster and diminishes its artistic appearance and at the same time is more expensive, this having been tried and found a failure. But, ac-
25 cording to my invention, additional colors may be applied to the natural, variegated colors and may be printed upon the yarn or upon the woven fabrics by any of the means employed for printing or dyeing the yarns
30 or fabrics used for carpets or rugs or any other textile fabric. Also in carrying out my invention the applied colors may be put on the variegated natural colored yarns more lightly than such colors have been commonly
35 used heretofore, thereby effecting a substantial saving in dyestuffs as well as enhancing the brilliancy of the color effects, and by this practice the original natural color tints are not suppressed but have a
40 superadded brilliance.

Furthermore, according to my invention, all that the spinner has to do is to put the several natural colors together at the original spinning. My invention includes and
45 covers any desired combinations of the undyed threads in the yarns. For instance, when three or more threads or strands are combined, I may employ one or more white and one or more light gray; one or more
50 white and one or more dark gray; one or more light gray and one or more dark gray, or any combination of natural colors of yarn.

The artistic effect produced by my inven-
55 tion I have found to be much superior to that obtainable by the older process. It is richer, more artistic, less expensive and lends

itself to uses to which the older yarns can-
not be applied.

I claim:

1. The variegated yarn produced by twist-
ing together strands of undyed woolen fibers
of different natural colors and applying
color at different separated points along the
yarn so produced. 60

2. The variegated yarn produced by twist-
ing together strands of undyed woolen fibers
of different natural colors and applying
different colors at different separated points
along the yarn so produced. 65

3. A patterned woven fabric comprising
in its weave a yarn composed of strands of
wool of different natural colors having dif-
ferent colors applied to different separated
parts along its length. 70

4. The process of manufacturing yarns
which consists in twisting together undyed
strands of wool of different natural colors
and applying coloring matter to separated
parts along the length of the composite yarn 80
so produced.

5. The process of manufacturing varie-
gated yarns which consists in twisting to-
gether undyed strands of wool of different
natural colors and applying coloring matter 85
of different colors to different separated
parts along the length of the composite yarn
so produced.

6. The process of manufacturing woven
fabric consisting in weaving weft threads
into a warp comprising variegated threads
composed of a number of strands of wool
of different natural colors and at some stage
of the manufacture of the fabric applying
coloring matter to separated parts of said 95
warp threads to form a pattern in the woven
fabric.

7. The process of manufacturing woven
fabric consisting in weaving weft threads
into a warp comprising variegated threads 100
composed of a number of strands of wool
of different natural colors and at some stage
of the manufacture of the fabric applying
coloring matter of different colors to differ-
ent separated parts of said warp threads 105
to form a pattern in the woven fabric.

8. A patterned woven fabric comprising
in its weave a yarn composed of strands of
wool of different natural colors having color-
ing matter applied to separated parts along 110
its length for thereby forming the pattern.

In testimony whereof I have affixed my
signature.

AUGUST G. FROMUTH.
